UNITED STATES PATENT OFFICE.

SVANTE R. W. M. BAGER, OF SOUTH MILWAUKEE, OTTO F. KAESER, OF MILWAUKEE, AND WERNER LEHMAN, OF SOUTH MILWAUKEE, WISCONSIN, ASSIGNORS TO BUCYRUS COMPANY, OF SOUTH MILWAUKEE, WISCONSIN, A CORPORATION OF WISCONSIN.

CREEPING-TRACTION MOUNTING FOR RAILWAY-TYPE EXCAVATORS.

Application filed August 31, 1921. Serial No. 497,206.

To all whom it may concern:

Be it known that we, SVANTE R. W. M. BAGER, OTTO F. KAESER, and WERNER LEHMAN, all citizens of the United States, and 5 residents of South Milwaukee, Milwaukee, and South Milwaukee, respectively, in the county of Milwaukee and State of Wisconsin, have invented new and useful Improvements in Creeping-Traction Mountings for 10 Railway-Type Excavators; and we do hereby declare that the following is a full, clear, and exact description thereof.

This invention relates to excavators and refers more particularly to a creeping traction mounting for railway type excavators.

Land excavators in general are divided into two types, namely: revolving and railway. In a revolving type excavator, the entire frame, carrying the engine and excavating elements, revolves through 360° on a pivot carried by the traction frame. In a railway type excavator the engine-carrying frame is integral with the traction frame and the excavating elements revolve by 25 themselves through about 180°. Revolving type excavators have in the past usually been carried by either railway wheels, traction wheels or creeping traction, with growing popularity of the last named. But, prior 30 to our invention, railway type excavators have always been carried on railway wheels, no practical means having been devised for placing them on creeping traction.

An object of our invention is to provide a 35 creeping traction mounting which either may be applied in the manufacture of railway type excavators or may equally well be applied for the conversion of those in the field.

40 The present excavators of the railway type are mounted on railway trucks and the rails are laid in short sections ahead of the forward trucks to enable the excavator to move ahead and reach fresh material. This constantly requires the service of several pitmen to carry the short sections ahead and lay on the tracks. The track shifting being dependent on the pitmen to be carried out promptly, results in a great loss of time 45 which is to be avoided.

Therefore, with the above in mind, it is another of the objects of this invention to provide a creeping traction mounting

whereby the excavator may be advanced 55 while digging away a bank ahead of it without requiring the laying of tracks to thus expedite the work.

In excavators of the class described, it is highly desirable that the same be capable 60 of conversion into either a railway type excavator or a creeping traction type excavator with a minimum of effort in order to facilitate the transportation of the same. It is, therefore, another object of this invention to provide means for permitting the 65 ready converting of a railway type excavator into a creeping traction type excavator.

A further object of the herein disclosed invention is to provide what may be termed 70 a combined creeping traction type and railway type excavator whereby the same may be advanced by means of its creeping traction means and be moved rearwardly upon a railway track, which may be laid in the rear thereof, without altering in any manner 75 the creeping traction mounting whereby time and labor are saved in shifting the excavator from an old cut into position for a new cut.

A still further object of this invention is 80 to provide a creeping traction mounting for railway type excavators in which the rear railway trucks have an endless traction member trained around adjacent truck wheels to afford suitable ground engaging means 85 and at the same time permit the rear truck to travel over rails without requiring the removal of said endless traction members, and forward ground engaging means carried by jack arms projected laterally from 90 the excavator frame adjacent the front railroad truck, the lower ground engaging faces of which are on a plane below that of the front truck wheels whereby said wheels will be free from the ground when the excavator 95 is supported by said front traction means and said front traction means will be free of the ground when the wheels of said front truck are engaging railway tracks.

It is a still further object of this invention 100 to provide an arrangement of creeping traction mountings for the supporting frame of the excavator whereby a three point suspension thereof is obtained.

And a still further object of this invention 105 resides in the provision of a creeping

traction mounting supported from a jack arm whereby the excavator frame is rigidly braced against overturning.

With the above and other objects in view which will appear as the description proceeds, our invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, we have illustrated one complete example of the physical embodiment of our invention constructed according to the best mode we have so far devised for the practical application of the principles thereof, and in which:

20 Figure 1 is a side view of the frame construction of an excavator illustrating our improved form of creeping traction mounting as applied thereto, parts of said frame being broken away;

25 Figure 2 is a fragmentary top plan view illustrating the guiding means of the excavator and the manner of drivingly connecting the front traction means with a drive shaft;

30 Figure 3 is a front end view, partly in section and partly in elevation, illustrating the manner of attaching the front traction means to the bolster frame and the manner of drivingly connecting the front traction means with a suitable drive shaft, and

Figure 4 is a detailed view partly in section and partly in elevation taken through Figure 1 on the plane of line 4-4.

40 Broadly speaking, this invention relates to a creeping traction mounting for a railway type excavator, which mounting is used to advance the excavator while digging away the bank ahead of it. When the excavator is mounted on railway tracks the rails have to be laid in short sections ahead of the forward trucks to enable the excavator to move ahead and reach fresh material, constantly requiring the services of several pitmen to carry the short sections ahead and lay the track, which results in a delay of the work. By mounting the excavator on creeping traction mountings, the track does not have to be laid until a long stretch has been completed and the excavator has to be moved rearwardly for some distance to begin a fresh cut.

45 During the forward movement of the excavator, a substantially track is preferably laid down therebehind as fast as it advances, which track is required as a loading track when the excavator has been moved back and started in the next adjacent cut. By the use of the track thus laid, the excavator can be moved backwards very rapidly and 50 is more easily steered and, in order to per-

mit proper use of the loading track, the railway traction mounting links are notched in the tread surface for engaging with a rail if desired. The front traction means are so designed and constructed as to permit the engagement of the forward truck wheels with the rail, and, at the same time, suspend the forward truck free of the ground when the front traction means support the excavator.

75 It will thus be readily apparent that the excavator can make its way ahead and carry beneath its forward end a standard railway truck which is not in use during the digging operation, but which is ready, immediately the excavator begins to move backward, to run on the previously laid rails, carrying the front traction mounting clear of the ground while the shovel is backed up to a new cut. During this backing movement, the traction chains need not be removed from the rear truck wheels as notches or grooves in the tread thereof engage the top of the rails and guide the excavator.

80 Referring now more particularly to the accompanying drawings, the numeral 5 designates the longitudinal beams of an excavator frame which is preferably mounted upon standard railway trucks 6 and 7 connected thereto by standard bolster constructions 8. The forward end of the excavator frame, to which the usual boom (not shown) is attached, is adapted to be supported and braced by laterally projecting jack arms which carry screw means (not shown) in 85 their outer ends for engagement with the ground.

90 In this invention the usual jack arms are removed and replaced by arms 9, see Figures 1, 2 and 3, the outer ends of which 95 terminate in journals 10 in which traction mounting frames 11 are pivotally mounted. The arms 9 are braced against movement either forwardly or rearwardly by brace arms 12 which extend from the excavator 100 frame to the outer ends of said arms.

105 Each frame 11 has a shaft 13 journaled in one end to which is secured a wheel 14, and in the other end a shaft 15, adjustably journaled to which is secured a wheel 16, 115 a traction chain 17 formed of a plurality of connected links being trained about said wheels. The lower run of each chain 17 is braced, intermediate wheels 14 and 16, by wheels 18 journaled in the frames 11 with 120 their lowermost faces substantially on a plane with the lowermost faces of wheels 14 and 16, and the tension of the traction chain may be readily regulated by adjusting shaft 15 through its setting means 19, which includes a jack screw carried by the frame and engaging the slidably mounted bearing blocks of shaft 15.

125 Journalized in bearings 20, transversely of the excavator frame, is a drive shaft 21, the 130

- outer ends of which terminate adjacent the sides of the excavator and have drive pinion gears 22 rotatably mounted thereon, each gear 22 being provided with clutch 5 jaws mating with similar jaws on a sliding jaw clutch 22', which is splined to shaft 21. By sliding one or the other of clutches 22' out of engagement, either or both of the chains 17 may be driven. Supported from 10 the excavator frame sides, substantially in alignment with bearings 20, are counter-shaft supports 23 which carry drive gears 24 in drive connection with wheels 14 of the front traction mountings. Fixed to each 15 shaft 13 is a driven gear 25 with which meshes a driven pinion 26 mounted on a shaft 27 journaled in the frame, said pinion being in approximate alignment with the adjacent gear 24.
- 20 The gears 24 and 26 have their adjacent faces provided with sockets 28 and 29, respectively, which are recessed to receive the adjacent end of a coupling drive pin 30. The pins 30 have a pivotal, but non-rotatable, engagement in the recesses of sockets 28 and 29 to provide a universal joint between the adjacent gears 24 and 26 whereby pivotal movement of the frames 11 will not disturb the traction drive connections. The 25 shaft 21 derives its power from a suitable engine (not shown) by means of a drive chain 31 trained about a chain sheave 32 carried by said shaft.
- 25 The lower tread face of each chain 17 is preferably on a lower plane than the lower-most portions of the front truck wheels 33 whereby the excavator can dig its way ahead advancing on its front traction mountings and carry the front railway truck 7 suspended clear of the ground. When the 30 excavator is moved rearwardly on previously laid rails 34, the forward traction mountings are suspended clear of the ground, as illustrated in Figure 3.
- 35 By supporting the forward creeping traction mountings from the jack arm, the necessity of providing braces extended from the sides of the excavator frame is eliminated, as will be apparent.
- 40 The rear creeping traction mountings consist of traction chains 35, formed of a plurality of pivotally connected links trained about the adjacent railway wheels 36. The links of chains 35 are formed with central 45 inwardly extending projections 37 which are channeled, as at 38, to provide a central rest or projection 39 for engagement with the treads of wheels 36 their flanges 40 engaging in either of the channels 38. By providing two channels 38, the chains 35 may be readily reversed, as will be obvious.
- 45 The links, forming chains 35, have their tread surface longitudinally channeled or grooved, as at 41, to receive the head of the 50 rails 34 whereby the excavator may be read-
- ily moved backward on the rails without necessitating the removal of chains 35. With this construction the converted rear truck 6 is capable of traveling on the ground or over a track without any alteration whatsoever.
- 55 When the excavator is traveling over the ground the same is preferably steered by the rear truck 6 to which is connected by radial arms 42 a segmental gear 43 slidably mounted within a guide way formed in a bracket member 44 secured to the excavator frame.
- 60 Journalized in bracket 44 is a shaft 45 on which is mounted a pinion 46 in mesh with the segmental steering gear 43, said shaft 65 also carrying a worm wheel 47 with which meshes a worm 48 carried by a steering drive shaft 49. The shaft 49 is connected with a suitable driving means (not shown) for controlling the guiding of the excavator as 70 will be readily apparent. When sharp turns are necessary, one or other of the jaw clutches 22' may be disengaged, thus driving only one creeping tractor chains 17.
- 75 After the work has been completed and it is desired to transfer the excavator to some other location at a distant point, the creeping traction mountings are removed and the excavator can then be drawn over the rails at a greater speed. However, when it is 80 merely desired to shift the position of the excavator to a new cut a half mile or so away, the creeping traction mountings are not removed and the excavator transported on the tracks as before described. By this 85 arrangement greater speed is obtained than that were the excavator transported over the ground on its creeping traction mountings, thus effecting considerable economy in 90 operation.
- 95 With the construction illustrated and described, the machine supporting frame has a three point suspension mounting which is desirable and permits the highest possible degree of efficiency. While this invention 100 has been illustrated and described as an excavating machine of the railway type, it will be appreciated that the features thereof are readily applicable to other types of 105 machines.
- 110 What is claimed is:
1. The hereindescribed method of handling an excavator, which consists in advancing the excavator supported entirely by ground engaging creeping traction means, 115 and in moving the excavator rearwardly by rail engaging means.
  2. The hereindescribed method of handling an excavator, which consists in advancing the excavator supported entirely by ground engaging creeping traction means, 120 in laying railway tracks in the rear as the excavator advances, and in moving the excavator rearwardly on the railway tracks.
  3. The hereindescribed method of han-

dling an excavator, which consists in advancing the excavator supported entirely by ground engaging creeping traction means while digging away a bank of material 5 ahead thereof, in laying a substantial track construction behind the excavator as it is advanced, and in moving the excavator rearwardly on the track.

4. In a railway type excavator including 10 front and rear railway trucks, of means for converting the same into a tractor type excavator and comprising traction links trained around the wheels of one of said trucks, and supporting traction members positioned one 15 at each side of the other truck.

5. In a railway type excavator including 20 front and rear railway trucks, of means for converting the same into a tractor type excavator and comprising traction links trained around the wheels of said rear railway truck, and creeping type traction members positioned at the sides of the front railway truck.

6. In a railway type excavator including 25 front and rear railway trucks, of means for converting the same into a tractor type excavator and comprising traction links trained around the wheels of said rear railway truck, and creeping type traction members positioned at the sides of the front railway 30 truck, the outer faces of the links trained around the rear truck wheels being grooved for engagement with a track.

7. In a railway type excavator including 35 front and rear railway trucks, of means for converting the same into a tractor type excavator and comprising traction links trained around the wheels of said rear railway truck, and creeping type traction members positioned at the sides of the front railway 40 truck, the outer faces of the links trained around the rear truck wheels being grooved for engagement with a track and the lower run of the front traction members being on 45 a different plane than the lowermost portion of the front truck wheels whereby said front truck hangs free when the front traction members support the excavator and said traction members are free of the ground 50 when the front truck wheels engage a track.

8. In a railway type excavator including 55 front and rear railway trucks, of means for converting the same into a tractor type excavator and comprising ground engaging traction means trained around the wheels of one of said trucks, supporting traction members positioned at the sides of the other truck, and means for moving the excavator on said traction means.

60 9. In a railway type excavator including front and rear railway trucks, of means for converting the same into a tractor type excavator and comprising ground engaging traction means trained around the wheels of 65 one of said trucks, supporting traction mem-

bers positioned at the sides of the other truck, and means for driving said last mentioned traction members to move the excavator.

10. In a railway type excavator including 70 front and rear railway trucks, of means for converting the same into a tractor type excavator and comprising ground engaging traction means trained around the wheels of one of said trucks, supporting traction members positioned at the sides of the other truck, means for moving the excavator, and means for guiding the excavator.

11. In a railway type excavator including 75 front and rear railway trucks, means for converting the same into a tractor type excavator and comprising ground engaging traction means trained around the wheels of the rear railway truck, traction members positioned at the sides of the front railway 80 truck, means for moving the excavator, and means connected with said rear railway truck for guiding the excavator.

12. In an excavating machine, a supporting 85 frame, a jack arm projected therefrom, and creeping traction means mounted on the outer end of the jack arm.

13. In an excavating machine, a supporting frame, jack arms projected from opposite sides thereof, and creeping traction 95 means mounted on the outer ends of the jack arms.

14. In an excavating machine, a supporting frame, a jack arm projected therefrom, means rigidly connecting the jack arm with 100 the supporting frame, and creeping traction means pivotally mounted on the outer end of the jack arm.

15. In an excavating machine, a supporting frame, a jack arm projected therefrom, 105 means rigidly connecting the jack arm with the supporting frame, creeping traction means, and means pivotally mounting the traction means on the jack arm for movement on a horizontal axis.

16. In an excavating machine, a supporting frame, jack arms projected from opposite sides thereof, brace means rigidly connecting the jack arms with the supporting frame, a traction mounting pivotally secured 115 on the outer end of each jack arm, and creeping traction means carried by the traction mountings.

17. In a railway type excavator, of means for converting the same into a creeping type 120 excavator and including jack arms projected from the sides thereof adjacent one of its supporting railway trucks, and traction means mounted on the outer ends of said jack arms.

18. In a railway type excavator, of means for converting the same into a creeping type 125 excavator and comprising jack arms projected from the sides thereof adjacent one of its supporting railway trucks, and traction means mounted on the outer ends of said jack arms.

- trucks, and traction means mounted on the outer ends of said jack arms, the ground engaging part of said traction means being on a plane lower than that 5 of the tread of the railway truck wheels whereby said railway truck hangs free when said traction means are in ground engaging position and said traction means hang free when the wheels engage tracks.
- 10 19. In a railway type excavator, of means for converting the same into a creeping type excavator and comprising jack arms projected from the sides thereof adjacent one of its supporting railway trucks, traction members mounted on the outer ends of said jack arms, and means for driving said traction members.
- 15 20. In a railway type excavator including railway supporting trucks, of means for converting the same into a creeping tractor type excavator and including a jack arm projected laterally from the excavator adjacent one truck, a traction frame carried by the outer end of said jack arm, spaced wheels journaled in said frame, and an endless traction member trained around said wheels.
- 20 21. In a railway type excavator including railway supporting trucks, of means for converting the same into a creeping tractor type excavator and including a jack arm projected laterally from the excavator adjacent one truck, a traction frame pivotally carried by the outer end of said jack arm, spaced wheels journaled in said frame, and an endless traction member trained around said wheels.
- 25 22. In a railway type excavator including railway supporting trucks, of means for converting the same into a creeping tractor type excavator and including a jack arm projected laterally from the excavator adjacent one truck, a traction frame carried by the other end of said jack arm, spaced wheels journaled in said frame, an endless traction member trained around said wheels, and power means for driving said traction member.
- 30 23. In an excavator, a jack arm, a traction frame mounted on the outer end of said jack arm, spaced guide wheels journaled in the opposite ends of said frame, an endless linked traction member trained around said guide wheels, a drive gear connected with one of said wheels, a drive shaft carried by the excavator, and a drive connection between said shaft and said gear for driving said traction member.
- 35 24. A creeping type traction mounting for an excavator comprising a traction frame, means for securing said frame to an excavator, spaced guide wheels carried by the frame, a traction tread member trained around said wheels, a tractor carried drive shaft, and means for drivingly connecting said drive shaft with one of said guide wheels and including an excavator carried gear connected with said shaft, a traction frame carried gear connected with one of said guide wheels, and a substantially universal drive connection between said gears.
- 40 25. A creeping type traction mounting for an excavator comprising a traction frame, means for securing said frame to an excavator, spaced guide wheels carried by the frame, a traction tread member trained around said wheels, a tractor carried drive shaft, and means for drivingly connecting said drive shaft with one of said guide wheels and including an excavator carried gear connected with said shaft, a traction frame carried gear connected with one of said guide wheels, a recessed shoulder formed on each of said gears, and a shaft having its ends pivotally but non-rotatably mounted in the recesses of said gear shoulders to provide a universal drive connection.
- 45 26. In a railway type excavator including front and rear railway trucks, means for converting the same, without altering the construction thereof, into a creeping tractor type excavator.
- 50 27. In a railway type excavator, means for converting the same into a creeping type excavator and comprising jack-arms projecting from the sides thereof, and creeping traction members mounted on the outer ends of said jack-arms.
- 55 28. In a railway type excavator, means for converting the same into a creeping type excavator and comprising jack-arms projecting from the sides thereof, creeping traction members mounted on the outer ends of said jack-arms, and means for driving said traction members.
- 60 29. In a railway type excavator including supporting railway trucks, means for converting the same into a creeping type excavator and comprising jack-arms projecting from the sides thereof adjacent one of its supporting railway trucks, and creeping traction members mounted on the outer ends of said jack-arms.
- 65 30. In a railway type excavator, including supporting railway trucks, means for converting the same into a creeping type excavator and comprising jack-arms projecting from the sides thereof adjacent one of its supporting railway trucks, creeping traction members mounted on the outer ends of said jack-arms, and means for driving said traction members.
- 70 31. In a railway type excavator, including front and rear railway trucks, jack-arms and jacks mounted on the ends thereof, of means for converting the same into a creeping traction excavator comprising a creeping traction truck adapted to be substituted for one railway truck and a creeping traction

truck adapted to be substituted for each jack at the end of each jack-arm.

32. In a railway type excavator, including front and rear railway trucks, jack-arms and jacks mounted on the ends thereof, of means for converting the same into a creeping traction excavator, comprising a creeping traction truck adapted to be substituted for one railway truck, and a jack-arm carrying a creeping traction truck adapted to be substituted for each jack-carrying jack-arm.

33. The method of converting a railway type excavator into a creeping traction exca-

vator, which consists in substituting a creeping traction truck for the rear railway truck, 15 in removing the forward railway truck, and in substituting jack-arm carried creeping traction means for each jack-carrying jack-arm.

In testimony that we claim the foregoing 20 we have hereunto set our hands at South Milwaukee, in the county of Milwaukee and State of Wisconsin.
